FOOD PRODUCTS

George G. Green, San Jose, Calif.

Application September 13, 1946, Serial No. 133,285

Term of patent 7 years

(Cl. D44—1)

To all whom it may concern:

Be it known that I, George G. Green, a citizen of the United States, residing at San Jose, in the county of Santa Clara and State of California, have invented a new, original, and ornamental Design for a Combined Mixer and Mold for Margarine and Other Food Products, of which the following is a specification, reference being had to the accompanying drawing, forming part thereof.

Fig. 1 is a perspective top view of a combined mixer and mold for margarine and other food products showing my new design.

Fig. 2 is a perspective bottom view of the combined mixer and mold shown in Fig. 1.

I claim:

The ornamental design for a combined mixer

and mold for margarine and other food products, as shown.

GEORGE G. GREEN.
